UNITED STATES PATENT OFFICE.

HERBERT CHAMPION HARRISON, OF LOCKPORT, NEW YORK, ASSIGNEE, BY MESNE
ASSIGNMENTS, TO HARRISON MANUFACTURING COMPANY, INC., OF LOCKPORT,
NEW YORK, A CORPORATION OF NEW YORK.

RADIATOR.

1,076,422.

Specification of Letters Patent.

Patented Oct. 21, 1913.

Application filed October 10, 1911. Serial No. 653,926.

To all whom it may concern:

Be it known that I, HERBERT C. HARRISON, a subject of the King of Great Britain, residing at Lockport, in the county of 5 Niagara and State of New York, have invented certain new and useful Improvements in Radiators; and I do hereby declare the following to be a full, clear, and exact description of the invention, such as 10 will enable others skilled in the art to which it appertains to make and use the same.

This invention relates to radiators especially adapted for flying machines, and 15 has for its object to produce a radiator of this nature which will be more efficient when carried by a flying machine or other fast moving object, than those heretofore employed, and will at the same time offer 20 much less resistance to the motion of the machine or vehicle.

To these ends the invention consists in the novel details of construction and combinations of parts more fully hereinafter 25 disclosed and particularly pointed out in the claim.

Referring to the accompanying drawings forming a part of this specification in which like numerals designate like parts in all the 30 views:—Figure 1 is a diagrammatic plan view of a flying machine equipped with my invention; Fig. 2 is an enlarged sectional plan view of a radiator made in accordance with my invention; and, Fig. 3 35 is a plan view of one of my radiators detached from the machine.

It is well known that the ordinary automobile radiators consisting of water tubes passing in one direction, and of air channels passing in a direction at right angles to the tubes, usually have the face of the radiator extending in a direction perpendicular to the line of travel. In other words, the air passages are generally located at 40 right angles to the line of travel so that the full broad side face of the radiator offers resistance to the motion of the vehicle. In fact, owing to the motion of the vehicle frequently not being more than a few miles per hour, it would seem essential 45 that the face of the radiator should extend at right angles to the line of travel, in order that a sufficient amount of air should be forced through the air passages to cool the

water in the water passages. When, however, such a radiator is placed upon a flying machine, as is the custom at present, the ordinary velocity of the flying machine is so very much greater than the ordinary velocity of an automobile, it no longer becomes necessary to locate the face of the radiator in a direction at right angles to the travel of the machine in order to get the necessary air pressure through the passages, and in fact the unnecessary resistance to flight which is engendered by so placing the radiator at right angles to the direction of flight is very objectionable.

According to my invention I obviate the above difficulties, as will be now more fully disclosed.

I indicates the seat of a flying machine, 2 the steering gear thereof, 3 one of the supporting planes of the machine, 4 the propeller, and 5 and 6 radiators located in their usual positions on such machine. Instead, however, of placing the front faces 7 of said radiators at right angles to the line of flight of the machine, I place said front faces at an acute angle thereto, say of about 10° to 15° or 20°, and in order that the air may be caught by and forced through the air passages 8 of said radiator, I locate said passages at an acute angle of say about 45° to the front face 7 of the radiator, as is best indicated in Fig. 2. The radiator is shown comprising a series of vertical perforated plates extending rearwardly from the front face 7 thereof at an acute angle; thereby providing a series of air passages 8 through which extend a series of water tubes 11. It results from this that the air impinging upon the front edges of said vertical series of angularly-extending plates in the direction of the arrows 9, shown in the various figures, which arrows indicate the direction of flight, will be caught by the passages 8 and forced out of the radiator at its rear face 10 after having been in intimate contact with the water tubes 11, all as will be clear from Fig. 2.

The action of air in passing through the radiator will be facilitated by the suction of the propeller, and therefore, owing to this fact, the angle of the front face to the line of flight may be made smaller than would otherwise be the case. Further, since the combined high velocity of the machine and

the suction of the propeller necessarily compels a comparatively large volume of air to pass through the radiator, the whole radiator may be made smaller and lighter
5 than would be the case if the front face 7 were located at right angles to the line of flight, as is now the practice. It, therefore, follows that not only does the particular location and construction of this radiator
10 decrease the resistance offered to the flight of the machine, but the further fact that it can be made smaller and lighter also aids in the general efficiency of the flying machine. It therefore results from the fact that the
15 flying machine is ordinarily propelled at a high velocity that, notwithstanding the diminished front area which comes in contact with the air, the speed will still be sufficiently high to force sufficient air through
20 the passages 8 to efficiently cool the water tubes 11.

The particular construction of the air passages and of the water tubes of the radiator does not form an integral portion of the
25 present invention, for it is evident that the disclosure above will apply to all constructions of radiators which may be found use-

ful in connection with flying machines. I have, therefore, only diagrammatically shown the construction of my radiator, and since it is obvious that those skilled in the art may vary the arrangement of parts as well as the details of construction without departing from the spirit of my invention, I do not wish to be limited to the above disclosure except as may be required by the claim. 30 35

What I claim is:—

In a machine adapted to be propelled at high speed, a radiator having vertical front 40 and side faces extending at acute angles to the line of travel, said radiator comprising a vertical series of perforated plates extending at an acute angle rearwardly from said front face, and a series of water tubes extending vertically in the passages between said angularly-extending plates. 45

In testimony whereof, I affix my signature, in presence of two witnesses.

HERBERT CHAMPION HARRISON.
